UNITED STATES PATENT OFFICE.

GABRIELLE M. P. YERKES, OF BROOKLYN, NEW YORK.

BRASSIÈRE.

Application filed December 21, 1923. Serial No. 682,025.

To all whom it may concern:

Be it known that I, GABRIELLE M. P. YERKES, a citizen of the United States, and resident of the borough of Brooklyn, in the city and State of New York, have invented a new and useful Improvement in Brassières, of which the following is a specification.

In brassières as commonly made, the diaphragm of the wearer is practically unsupported and the diaphragm is thus allowed to unduly protrude. Bones have been placed in various positions in the brassière in the attempt to correct this fault.

The object of my invention is to provide a very comfortable and well fitting garment which will properly and effectively support the diaphragm of the wearer, without the use of bones in the garment for this purpose.

My invention consists of a brassière provided with a boneless diaphragm support and more particularly a brassière having its front provided with a plurality of boneless non-elastic diaphragm supporting members, which members preferably overlap; reinforcing straps being provided for assisting in holding the diaphragm supporting portion of the brassière in proper position.

A practical embodiment of my invention is represented in the accompanying drawings, in which—

Fig. 1 represents the brassière in front elevation as in use.

Fig. 2 represents the brassière in side elevation as in use.

Fig. 3 represents an enlarged diagrammatic section taken vertically through the front of the brassière in the plane of the line III—III of Fig. 1, looking in the direction of the arrows.

Fig. 4 represents a detail enlarged diagrammatic section taken in the plane of the line IV—IV of Fig. 2, looking in the direction of the arrows.

Fig. 5 represents an outside view of the brassière laid out flat.

Fig. 6 represents an inside view of the same.

The brassière is shown as made up of non-elastic members, the middle front member

being denoted by 1, the two side front members by 2, 3, the two side back members by 4, 5, the two elastic gores by 6, 7, and the two middle back members by 8, 9. Any suitable fastening means such as hooks and eyes 10 and 11 may be employed for uniting the two middle back members. The brassière is also provided with suitable shoulder straps 12, 13.

The front of the brassière is provided with a boneless non-elastic diaphragm support, which support in the present instance comprises the two overlapping members 14, 15, which extend across the lower portion of the middle front member 1 from side to side thereof, forming three thicknesses of material at the overlapping portions. The upper edges of these members may be inclined upwardly from the sides of the member 1 to a median line.

The two side front members 2, 3 are provided with reinforcing boneless non-elastic straps 16, 17 and 18, 19, which extend from the upper corners of the supporting members laterally and upwardly across the side front members for assisting in holding the diaphragm supporting portion of the brassière in proper position.

From the above description it will be seen that I have provided a brassière in which the diaphragm of the wearer is properly supported without the use of bones for this purpose, thereby making the brassière much more comfortable.

It is evident that various changes may be resorted to in the construction, form and arrangement of the several parts without departing from the spirit and scope of my invention; hence, I do not wish to be limited to the particular embodiment herein shown and described, but

What I claim is:—

1. A brassière composed of non-elastic middle and side front members, non-elastic side and middle back members, and elastic gores secured between the side and middle back members, the middle front member being provided with a flexible non-elastic diaphragm support free from stays extending across the lower portion thereof.

2. A brassière composed of non-elastic middle and side front members, non-elastic

side and middle back members, and elastic gores between the side and middle back members, the middle front member being provided with a non-elastic diaphragm support extending across the lower portion thereof and the side front members being provided with spaced reinforcing straps ex-

tending laterally across the same diagonally upward from the said diaphragm support.

In testimony that I claim the foregoing as my invention I have signed my name this 18th day of December, 1923.

GABRIELLE M. P. YERKES.
